UNITED STATES PATENT OFFICE

HERMANN OBERSCHULTE, OF RUHR, GERMANY

DOLPHIN

Application filed December 18, 1930, Serial No. 503,292, and in Germany October 29, 1929.

My invention relates to dolphins or mooring piles composed of vertically rammed metal sections, such as channel- or Z-section sheet-piling members.

5 In accordance with my invention each two or more separate sections are assembled to form separate boxes or pipes or equivalent by means of locking joints, welding, bolts, rivets, bands or other connecting means.

10 A feature of my invention resides in assembling several such boxes or equivalent to a complete unit by the same connecting means.

Now, in order to absorb the impact of the ship, the dolphin must possess considerable powers of resistance and also a high degree of elasticity. To obtain both properties, the several sheet-piling members must, as regards the portion which is rammed into the ground, be as rigid as possible, whereas the upper 20 portion, which is not rammed into the ground, must possess, in itself, a certain mobility. I attain this object by applying the aforesaid connecting means to only the lower or embedded portion which has to stand the 25 heaviest bending stresses.

Embodiments of my invention are illustrated by way of example on the accompanying drawings whereon:

Fig. 1 is an elevation of one of my dolphins 30 on the side on which the ship is moored;

Fig. 2 represents a vertical section through the dolphin;

Fig. 3 is a cross section;

Fig. 4 is a partial section corresponding to 35 Fig. 2 and showing the mooring member on a larger scale;

Fig. 5 is a fragmentary cross section along the line V—V of Fig. 2 with parts omitted;

Fig. 6 is a plan of another embodiment; 40 and

Fig. 7 is a section, on a larger scale, of a detail of the arrangement according to Fig. 6.

Referring to the drawings, the channel-section sheet-piling members *a* are disposed 45 in pairs, with their open sides facing, so as to form boxes, and they are firmly secured together, at the lower ends, by locking members *b*, *b'*. The locking members *b*, *b'* are provided only at the ends of the piling which 50 will be embedded in the ground, and termi-

nate on the piling at a point substantially at the ground level.

Several (for example three) of such box piles are rammed in juxtaposition, each succeeding pile engaging with the flanges of the 55 channels in the locking member *b* of the preceding pile. Another row of box piles is then rammed, these being composed in the same manner, and so that their flat sides *a'* come into contact, or nearly so, with the corresponding sides *a'* of the row first rammed. The pile members in this second row are united in the manner already described, and a third row can then be rammed, and so on. The number of the box piles and the number 60 of rows will depend on the size and shape of the desired dolphin. In order to ensure firmer combination, screw bolts *e*, holding the successive rows together, can be inserted through the surfaces *a'* above but close to 65 the ground level.

The locking members *b*, *b'* can also be secured to the members *a* by welding, and, as indicated in Figs. 6 and 7, the channel irons 70 can also be welded directly together at *i*.

For mooring the ships, mooring members *c* are housed in the recesses *k* of the piles, said members being of the usual design and anchored by means of bolts *c'*. Bollards *d* can also be attached, thus making provision for 75 variations in the level of the water.

All the bolt connections can be disposed in such a manner that the dolphin is perfectly smooth on the outside, thus rendering wooden fenders unnecessary. In the drawings, however, wooden fenders *h* are shown adjacent 80 to the dolphin.

It is important that the rigid connection between the sheet-piling members *a* should be substantially confined to the embedded 85 portion of the rammed rows, whether connection is effected by welding or by means of locking members, so that the upper portion will have a high degree of resiliency.

In the embodiment according to Figs. 6 and 7, the piles, each composed of two channel-irons *a* and welded together at the lower end, are spaced apart and rammed. They are supported, at the upper end by interposed timbers *f* and held together by a brac- 95 100

ing g and turn buckles g' . In this case also, wooden fenders h are provided at the sides. The boxes may also be composed of sections differing in shape from those specified.

5 Having now particularly described and ascertained the nature of my said invention and in what manner the same is to be performed, I declare that what I claim is:

1. A dolphin or mooring post comprising a plurality of vertical hollow metal piles, each pile comprising a plurality of interconnected vertical sections, the piles being rigidly interconnected only at their lower ends and along lengths thereof corresponding to the length to be embedded in the ground and being unconnected along their remaining portions to provide a resilient structure above the ground level for the purposes specified.
- 10 2. A dolphin or mooring post comprising a plurality of metal piles grouped in several contiguous rows, each pile comprising a plurality of vertical sections, means connecting the sections to form the rows of piles, and means connecting the rows of piles to form a substantially rectangular mooring post, said connecting means being located only on the lower portions of the piles from a point adjacent the ground level to the lower ends of the piles to provide a rigid structure below the ground level and a resilient structure above the ground level.
- 15 3. A dolphin or mooring post comprising a plurality of vertical metallic piles having portions embedded in the ground and portions above the ground level, said piles being spaced apart from each other a distance substantially equal to the cross sectional area of each pile, inserts between the piles, and means rigidly connecting the embedded portions of said piles and inserts together, the remainder of said piles and inserts being unconnected for the purpose specified.
- 20 4. In testimony whereof I have affixed my signature.
- 25 5. HERMANN OBERSCHULTE.
